UNITED STATES PATENT OFFICE.

GEORGE W. BLAIR, OF MISHAWAKA, INDIANA, ASSIGNOR TO MISHAWAKA RUBBER AND WOOLEN MANUFACTURING COMPANY, OF MISHAWAKA, INDIANA, A CORPORATION OF INDIANA.

DESIGN FOR AN OVERSHOE.

Application filed March 15, 1924. Serial No. 8,940. Term of patent 14 years.

To all whom it may concern:

I, GEORGE W. BLAIR, a citizen of the United States, residing in Mishawaka, county of St. Joseph, and State of Indiana, have invented a new, original, and ornamental Design for an Overshoe, of which the following is a specification, reference being had to the accompanying drawing, forming a part thereof.

The figure is a perspective view of an overshoe showing my new design.

I claim:

The ornamental design for an overshoe, substantially as shown.

GEORGE W. BLAIR.
